UNITED STATES PATENT OFFICE

JOSEPH D. NIEDERLITZ, OF ROCHESTER, NEW YORK

DESIGN FOR A PACK OF PLAYING CARDS

Application filed August 14, 1929. Serial No. 32,404. Term of patent 7 years.

To all whom it may concern:

Be it known that I, JOSEPH D. NIEDERLITZ, a citizen of the United States, residing at Rochester, in the county of Monroe and State of New York, have invented a new, original, and ornamental Design for a Pack of Playing Cards, of which the following is a specification, reference being had to the accompanying drawing, forming part thereof.

In the drawings:

Fig. 1 is a fragmentary face view of a pack of playing cards showing my new design; and

Fig. 2 is a view of the back of one of the cards and the same ornamentation appears on the backs of the entire pack of cards.

The essential feature of the front faces of the cards is an outer rectangular frame containing a domino representation, an intermediate rectangular frame symmetrically arranged about the first frame and a rectangular border symmetrically arranged about the second frame and containing a playing card symbol. The pack consists of fifty-four cards and has representations thereon for two sets each of hearts, clubs, diamonds and spades.

I claim:

The ornamental design for a pack of playing cards, as shown and described.

JOSEPH D. NIEDERLITZ.
